UNITED STATES PATENT OFFICE.

SAMUEL G. GREEN, OF GRAY, GEORGIA.

REAR SIGHT FOR GUNS.

Application filed June 15, 1925. Serial No. 37,352.

(GRANTED UNDER THE ACT OF MARCH 3, 1883; 22 STAT. L. 625.)

The invention described herein may be used by the Government, or any of its officers or employees in prosecution of work for the Government, or by any other person in the 5 United States, without payment to me of any royalty thereon, in accordance with the act of March 3, 1883.

This invention relates to a rear sight for guns and is especially adapted for use with 10 machine guns.

The problem of aiming a gun at a ground target is entirely different from that of aiming the gun at an aerial target. The latter involves additional considerations due to the 15 speed of an aeroplane and its ability to maneuver in an unrestricted field. A sighting system which is primarily designed for one class of targets can not, as a rule, be used with any degree of accuracy against the 20 other class.

The principal object of the present invention is to provide a combination rear sight for a sighting system which in addition to being simpler in constructional details than 25 the customary single purpose sight contains elements for sighting both ground and aerial targets. The respective sighting apertures are provided at each end of a drift slide which is connected in a novel and simple 30 manner to a main slide which embraces the sight leaf in the customary manner. Provision is made adjacent the lower peep sight aperture to afford the gunner the advantage of a large field in picking up a target.

35 A further object of the invention is to provide an index plate for reading the range elevations which may be adjusted to proper position after proof firing the gun.

The improvements are all incorporated in 40 the slide units so that they may be readily mounted on sight leafs now in use, replacing the single purpose sight.

To these and other ends, the invention consists in the construction, arrangement, and 45 combination of elements, described herein-after and pointed out in the claims forming a part of this specification.

A practical embodiment of my invention is illustrated in the accompanying drawings, 50 wherein:

Fig. 1 is a view in rear elevation of a sight constructed in accordance with the invention and showing the leaf in raised position;

Fig. 2 is a longitudinal section on the line 55 2-2 of Fig. 1;

Fig. 3 is a cross section on the line 3-3 of Fig. 1;

Fig. 4 is a detail view of the drift slide;

Fig. 5 is a detail view of the base plate of the main slide;

Fig. 6 is a detail view of the adjusting plate;

Fig. 7 is an end view of the adjusting plate;

Fig. 8 is a detail view of the main slide 65 cap plate; and

Fig. 9 is a detail view of the half nut.

Referring to the drawings by numerals of reference:

There is shown a base 6 adapted to be 70 mounted on a support (not shown) fixed to a gun and on the base is pivoted a slotted sight leaf 7 graduated in values of range. The leaf is of conventional design being formed with an inclined guideway 8 and 75 mounting a micrometer elevating screw 9.

The sliding units of the sight consist of a drift slide 10 disposed in the inclined guideway 8 and a main slide 11 to which it is connected for movement and which embraces 80 the leaf and is constrained thereby to vertical movement.

The main slide is preferably made up of two units, one being a base plate 12 grooved as at 13 to receive the leaf and have a sliding fit thereon, and the other being a cap plate 14 which may be secured to the base plate by screws 15. The base plate includes a lug 16 disposed in the slot of the leaf when the main slide is assembled and this lug 90 houses a spring 17 which acts to normally hold a half nut 18 in engagement with the elevating screw 9. The half nut is carried in a recess 19 in the base plate and is formed with an angled portion 20 adapted to engage 95 the side of the leaf to limit its movement when pressed inwardly by means of a thumb nut 21 pinned to its outer extremity.

The drift slide 10 is provided with two sighting apertures, the upper aperture 22 100 being used in aiming at aerial targets and the lower peep sight aperture 23 used for ground targets. Above the peep sight 23 is an arcuate aperture 24 which is provided as an orienting sight for the purpose of affording a large field of view to enable the gunner to readily pick up the target. This arrangement affords a peep sight having all the advantages of an open sight without its disadvantages since the eye is not cognizant 105 110

of the opening 24 when moved to focus through the peep sight 23.

In order that the drift slide may be moved in its inclined guideway through the instrumentality of the main slide which is constrained to vertical movement it is provided, front and rear, with lugs 25 and 26 respectively bearing against the upper side of the cap plate 14 and the under side of the lug 16 on the base plate 12.

Due to variations in fabrication, the accuracy of the adjustment of the sights must be verified by proof firing the gun or otherwise testing it to establish a correct index 15 or zero. Inasmuch as the range scale inscribed on the sight leaf is fixed it is proposed to provide a movable index plate for reading the ranges. The index plate 27 is therefore formed with slots 28 whereby it 20 may be adjustably secured to the cap plate by screws 29. The plate is formed with a pair of pointers 30 for reading the ranges on both sides of the leaf. It is further recessed as at 31 to permit its movement 25 without interference with a battle sight 14' on the cap plate 14.

The sighting aperture 22 is in the present instance dimensioned to be set at a range of two thousand (2,000) when aiming at aerial 30 targets, this setting being dependent on the type of front sight employed in conjunction therewith.

I claim:

1. A rear sight for guns embodying a 35 slotted leaf having an inclined guideway, an elevating screw journaled in the leaf, a drift slide disposed in the guideway and formed at its upper end with an aperture for sighting aerial targets and at its lower end with 40 an aperture for sighting ground targets, said slide further formed with an arcuate opening above the lower sighting aperture for the purpose of establishing a field of view, a main slide embracing the leaf and including 45 a base plate grooved to receive the leaf, and a cap plate secured thereto, a battle sight carried by the cap plate, a half nut carried by the base plate and movable into and out of engagement with the elevating 50 screw, lugs on the front and rear of the drift slide and oppositely bearing against the cap plate and the base plate respectively, and an index plate adjustably secured to the cap plate and recessed to receive the battle 55 sight.

2. A rear sight for guns embodying a slotted leaf having an inclined guideway, an elevating screw journaled in the leaf, a drift slide disposed in the guideway and formed 60 at its upper end with an aperture for sighting aerial targets and at its lower end with an aperture for sighting ground targets, a main slide embracing the leaf and including

a base plate grooved to receive the leaf and a cap plate secured thereto, a half nut carried by the base plate and movable into and out of engagement with the elevating screw, lugs on the front and rear of the drift slide for oppositely bearing against the cap plate and the base plate respectively, and an index 65 70 plate adjustably secured to the cap plate.

3. A rear sight for guns embodying a slotted leaf having an inclined guideway, an elevating screw journaled in the leaf, a drift slide disposed in the guideway and formed 75 at its upper end with an aperture for sighting aerial targets and at its lower end with a peep sight for sighting ground targets, a main slide embracing the leaf, lugs on the front and rear of the drift slide for oppositely bearing against the upper and lower sides of the main slide respectively, a battle sight on the main slide, a half nut carried by the main slide and movable into and out of engagement with the elevating screw, 80 and an index plate adjustably secured to the main slide and recessed to receive the battle sight.

4. A rear sight for guns embodying a slotted leaf having an inclined guideway, an elevating screw journaled in the leaf, a drift slide disposed in the guideway and formed 85 at its upper end with an aperture for sighting aerial targets and at its lower end with a peep sight for sighting ground targets, a 90 main slide embracing the leaf, a connection between the drift and main slides whereby they are movable in unison, a half nut carried by the main slide and movable into and out of engagement with the elevating screw, 95 and a range index plate adjustably secured to the main slide.

5. A rear sight for guns embodying a leaf, a slide adjustable thereon and having a peep sight, and said slide being provided with 105 an arcuate opening above and adjacent the peep sight having the sight opening as a center to establish a field of view to assist in picking up a target.

6. A rear sight for guns embodying a slotted leaf having an inclined guideway, a drift slide in the guideway provided with a sighting aperture, a main slide embracing the leaf and connected to the drift slide, a battle sight on the main slide, and an adjustable range index plate attached to the main slide and recessed to accommodate the battle sight.

7. A rear sight for guns embodying a slotted leaf having an inclined guideway, a drift slide in the guideway provided with a sighting aperture, a main slide embracing the leaf and connected to the drift slide, and an adjustable range index plate attached to the main slide.

SAMUEL G. GREEN.
